UNITED STATES PATENT OFFICE.

ST. JOHN CLARKE, OF BOGOTA, NEW JERSEY.

SHORE-PROTECTOR.

1,352,429.

Specification of Letters Patent. Patented Sept. 14, 1920.

Application filed January 14, 1918. Serial No. 211,766.

To all whom it may concern:

Be it known that I, ST. JOHN CLARKE, a citizen of the United States, and resident of Bogota, in the county of Bergen and 5 State of New Jersey, have invented certain new and useful Improvements in Shore-Protectors, of which the following is a specification.

My present invention relates to means for 10 protecting beaches and banks, particularly beaches of sandy or shifting material exposed to the varying and alternating action of storms, tides and waves, but it is also capable of useful application to shores and 15 banks of other materials exposed to erosion by less violent forces.

It includes as a central feature, a cellular earth-trapping, water-draining construction 20 preferably made of reinforced concrete or similar material. Its novel features are of utility when built in a single structure and used on steep banks either with or without foundations or other special securing means, but it has special advantages and functions 25 when made up in separate sections or slab-like units, and laid as a sort of pavement on sloping beaches or water-washed shores. Its 30 peculiar features of construction adapt it for effectively gripping the earth or sand of such surfaces so that it retains the material and, where the slope is not too great, the slab is in turn retained by the material from slipping downward along the slope. Thus 35 each section or slab unit may be independently supported by the surface on which it lies even on a considerable incline without the necessity of a foundation or other securing means.

Each section consists of a relatively thin 40 slab, structurally strengthened by integral downwardly projecting ribs, and formed with one or more holes through which earth or sand may be filled in when the slab is laid, ribs downward, on the ground or beach surface 45 face to be retained thereby. In addition to their function as strengthening ribs, the ribs serve as partitions and the slabs are so laid that there will be a series of these partitions extending lengthwise of the beach, thus subdividing and contouring the material of the 50 surface into a series of approximately parallel earth or sand ridges which extend up-

ward into the spaces between the partition ribs. This tends to break up flow or seepage of water beneath the slabs in the direction 55 of the slope of the beach.

It is also desirable to break up lateral flow and erosion which may result from flow of water through seams between slabs or through apertures in the upper surface of 60 the slab. Hence I preferably provide a second series of depending partition ribs, preferably at right angles to those first mentioned, and consequently extend up and down the slope of the beach. For convenience the partition ribs extending lengthwise along the beach may be termed longitudinal ribs or flanges while those extending up and down the slope may be termed transverse ribs or flanges.

When slabs with both sets of partition ribs are laid in place they constitute a system of open bottom boxes or cell units, the walls of which are adapted to partition off and subdivide the surface of the beach or 75 bank to a desired predetermined depth, into frustums of earth or sand of relatively small area. Each such frustum is substantially protected by the slab, the latter forming a flat top or cover extending over a substantial part of the area of each cell but leaving an aperture through which the sand or other material may be introduced to fill in the beach surface to or above the top of 80 the cell.

The depth and spacing of the longitudinal partition ribs are predetermined with reference to the slope and shiftiness of the material, greater depth and closer spacing being required where slope is considerable or 90 the material very shifting.

The size and location of the aperture in the cell cover are predetermined with reference to the angle of the shore or bank so that water finding its way into the open 95 bottom of any cell, must flow upward in that cell in order to escape from the aperture in the cover. To this end, and for the better protection of the filling material, I prefer that the aperture in the cover of each cell 100 be located nearer the upper than the lower portion of the cover of the cell. The distance between the longitudinal partition ribs is preferably considerably greater than

the depth of said ribs and said ribs are preferably as thin as consistent with the strength required for such a structure. This will give the frustums of sand or other beach material which project up into the open bottomed cells a height proportioned to horizontal section which will be adapted to give the slab a hold or anchorage against sliding down the beach, which will be the best possible in view of the shiftiness of the sand or other material.

The transverse partition ribs may be farther apart than the longitudinal ribs because there is less necessity for gripping the beach in a direction to prevent lateral shifting of the cell units along the beach and also because the wash along the beach is usually much less than the wash up and down the beach. This makes the open-bottom boxes or cells and sand frustums therein oblong in horizontal outline. For similar reasons the apertures in the tops of the cells may be correspondingly oblong without too greatly exposing the material of the beach to being washed out of the cells.

As will be evident from the foregoing, the width of the boxes or cell units is predetermined within limits by the slope of the beach and in most practical cases, this dimension will be found to be such that a single cell will not have the weight and area required for stability against heavy waves. For this reason and also for convenience in manufacture, I prefer to embody the above described structural features in a monolith or slab large enough to include a considerable number of the longitudinal partition ribs. For structural strength with economy of material there should also be several of the transverse ribs so that the slab will comprise a considerable number of the box-like cell units, say 9 to 16 or even 25. The slabs must not be too big for structural rigidity however and as economy of material requires that the flanges be not too thick or too deep, the size of the slabs is limited.

The above described slab structure is preferably so laid as to establish a condition of mutual coöperation between the beach material and the slabs so that the material will retain the slabs against slipping down the slope while the slabs in turn will encourage deposit and discourage washing out of the material of the beach, the only opposition to the natural breaking of the waves being the upper and lower edges of the apertures in the tops of the cells. Hence when used according to my preferred method, the slabs will be laid on a slope bearing a definite relation to the natural slope of the beach and the natural angle of repose of the material of which it is composed and the preferable slopes are less, usually considerably less than 30° from the horizontal.

65 The above and other details of my inven-

tion as well as of its nature and objects may be more fully understood from the following description in connection with the accompanying drawings in which—

Figure 1 is a top plan view of a shore protected in accordance with my invention;

Fig. 2 is a vertical section on the line *x*—*x*, Fig. 1;

Fig. 3 is a top plan view of a modified construction; and

Fig. 4 is a vertical section on the line *y*—*y* of Fig. 3.

As indicated in Figs. 1 and 3, the slabs, 1, 1 etc. are laid in horizontal rows extending along the beach as far as the shore protection is required. Similar slabs 2, 2, 2 and 3, 3, 3 and 4, 4, 4 are laid at successively higher levels so as to cover the surface of the beach, preferably from below low water level, indicated at A, up the slope of the beach B as far as protection is desired, preferably above normal high water mark.

The slabs may be laid with their edges nearly or quite in contact with each other, as in Fig. 3, but I prefer to separate them slightly and also to shape their edges so that they will be less likely to bind against each other or become broken in case of unequal settling or slight shifting of one slab with respect to the others. Preferably the joints or spaces between slabs in the successively higher rows 1, 2, 3, 4 break joints so that flow of water up and down the slope of the beach will be less likely to erode the sand between adjacent slabs. There is not the same objection to alining the rows lengthwise of the beach, since the natural flow of surf will be mostly up and down the slope transversely of the joints between the rows, and there is more tendency to wash the sand into these joints than out of them.

In case a bulk-head or break-water C is employed the upper row of slabs may have their upper edges built or cast into the structure as shown in Figs. 2 and 4.

In the form shown in Figs. 1 and 2 the slabs are constructed with longitudinal partition ribs 6, 7, 8, 9, 10 and transverse ribs 11, 12, 13, 14 thus forming the bottom surface of the slab into 12 box-like cell units. The latter are oblong with their longer sides lengthwise of the beach so that as shown in Fig. 2, each slab has four of the cell compartments in the line of slope of the beach, and as shown in Fig. 1, three of them lengthwise of the beach.

The tops of the cell compartments are preferably closed in except for the apertures 15 which are located close to the up-slope partition rib of the cell, either flush with it as shown in Figs. 1 and 2 or nearly so as shown in Figs. 3 and 4. Thus the upper surface of the slab is substantially a plain surface with suitable openings through which each compartment may be filled in

either by hand, as when the slab is first laid or subsequently by deposit and trapping of sand brought up by action of the surf.

For the above reason I prefer to make the 5 slabs up in multiple units say about ten feet by ten feet or twelve feet by twelve feet for the square forms indicated in Fig. 3 or say eight feet by ten feet or ten feet by twelve feet for the forms shown in Fig. 1. In such 10 case the slabs and partition ribs may be 2 or 3 inches thick. The depth of the ribs will be say eight to ten inches or more according to the slope and material of the beach and in most cases the longitudinal partition 15 rib may be spaced apart a distance 2 or more times the depth of the ribs.

It will be obvious, however, that the number of compartments and the size of the 20 slabs may be greatly varied and that for some purposes it would be practical to use 25 slabs say four feet by four feet having only a single compartment. In such case the partition ribs may be inset say six or eight inches from the edges of the slab.

It is not necessary that all of the ribs be 30 of the same depth or thickness, since some of them may be made deeper than others, for a portion or all of their length, for the purpose of increasing the structural strength 35 of the slab, or for the purpose of deeper partitioning of the beach at certain points or in certain directions, or for the purpose of affording additional anchorage of the slab against slipping down the beach, or 40 for protecting the edges of the slab, as for instance the lower edge of the lowermost slab of the upper edge of an uppermost slab.

Illustrative examples are shown as applied to slabs 1 and 2. On slab 1, the lower- 45 most longitudinal rib is shown as extended downward a considerable distance as at 21 to afford protection against undermining. It may be braced by a bracket-like extension 50 of an adjacent portion of one or more off the transverse ribs. Slab 2 is shown as having its central longitudinal rib extended 55 downward as at 23 and braced on both sides by bracket-like downward extensions 24, 25 of one or more of the transverse ribs. This 60 would be useful as additional central anchoring of the slab.

I prefer, however, that the slabs be of 65 equal size and the partition ribs of equal depth suitable to the slope and material of a given beach, since in case of any slight 70 shifting or settling of the slabs the settling is likely to be more uniform if the lower edges of the partitions lie in the same plane, than it is if one portion of the area of the 75 slab engages the material of the beach more deeply than another portion.

It is impracticable to show or describe all 80 of the possible conditions of the sand or other filling material with respect to the 85 cellular compartments of the slabs. It will

be understood, however, that in many cases the slabs or some of them may be buried under the sand, especially during weather favorable to beach building. Under certain average conditions, however, it will be evident that even dry sand will substantially 70 fill the compartments as in Fig. 4. In Fig. 2, I have indicated the sand as having been removed from certain of the compartments of slab 2, so as to expose more or less of 75 the rear surface of the uppermost partition of the compartment. In such case the compartment opening forms a trap well adapted to catch sand carried up and down the slope by the breakers, and in case of seepage of 80 water into the compartments from beneath, the sand will naturally settle out and fill the compartment while the water will escape through the opening in the top surface. The 85 use of multiple compartments for a single slab averages the variable support which may be furnished by a large number of the cells so that where some of them are partially or even wholly empty the slab may be still adequately supported against settling 90 by other cells which are more completely filled. In case of a wash-out completely undermining one or more of the longitudinal partition ribs, the cavity thus formed will merely constitute a larger trap adapted to 95 be filled in either automatically or by hand through the slab openings in the same manner as single compartments are filled.

Slabs of the smaller sizes above indicated 100 will not be too large for casting at a suitable central plant for transportation and laying upon shores at a distant point. I prefer, however, to employ the larger unit, casting them adjacent to the position in which they are to be used. For convenience 105 in manufacture, it is preferable to mold or cast them flat face downward upon a suitable bed with box molds defining the partition ribs. The reinforcing rods 41, 41, 42, 42 may be most conveniently located adjacent 110 the tops and bottoms of the partition ribs since this affords maximum transverse or truss strength for these members.

If the mold is located closely adjacent the place where the slab is to be laid, the latter 115 may be of very considerable size since in such case the only handling the finished slab will require is turning over ribs downward off of the casting bed on to the beach where the compartments may be filled in with sand 120 or other material which will soon settle into and form part of the beach surface.

I claim:

1. A shore protecting structure adapted to be laid on sloping shores comprising a 125 slab formed on its under face with sets of intersecting partition ribs constituting open bottom cellular compartments and supporting the slab a considerable distance above the surface of the beach on which it is laid, 130

said slab being formed with filler openings through which each compartment may be filled.

2. A shore protecting structure adapted to be laid on sloping shores comprising a slab formed on its under face with sets of intersecting partition ribs constituting open bottom cellular compartments and supporting the slab a considerable distance above 10 the surface of the beach on which it is laid, said slab being formed with filler openings adjacent the up-slope partition of each compartment.

3. A shore protecting structure adapted 15 to be laid on sloping shores comprising a slab formed on its under face with sets of intersecting partition ribs constituting open bottom cellular compartments and supporting the slab a considerable distance above 20 the surface of the beach on which it is laid, said slab being formed with filler openings relatively remote from the down-slope partition of each compartment.

4. A shore protecting structure adapted 25 to be laid on sloping shores comprising a slab formed on its under face with sets of intersecting partition ribs constituting open bottom cellular compartments and supporting the slab a considerable distance above 30 the surface of the beach on which it is laid,

said slab being formed with filler openings adjacent the up-slope partition of each compartment and relatively remote from the down-slope partition and from the side partitions thereof.

5. A shore protecting unit comprising a slab having its under surface provided with longitudinal and transverse ribs, and a filling aperture through which the space between partition ribs may be filled. 35 40

6. A shore protecting unit comprising a slab having its under surface provided with longitudinal and transverse ribs, and a filling aperture through which the space between partition ribs may be filled, said apertures being much narrower than the space 45 between the ribs.

7. A shore protecting unit comprising a slab having its under surface provided with longitudinal and transverse ribs, and a filling aperture through which the space between partition ribs may be filled, said apertures being much narrower than the space 50 between the ribs and located nearer one rib than the others. 55

Signed at New York city, in the county of New York, and State of New York this 12th day of January, A. D. 1918.

ST. JOHN CLARKE.
